US0D1042361S

(12) **United States Design Patent** (10) **Patent No.:** **US D1,042,361 S**
(45) **Date of Patent:** **** Sep. 17, 2024**

(54) **LED PROXIMITY SWITCH**

(71) Applicant: **Curtis Alan Roys**, Fredericksburg, TX (US)

(72) Inventor: **Curtis Alan Roys**, Fredericksburg, TX (US)

(**) Term: **15 Years**

(21) Appl. No.: **29/791,837**

(22) Filed: **Feb. 11, 2022**

Related U.S. Application Data

(63) Continuation-in-part of application No. 29/754,118, filed on Oct. 6, 2020, now Pat. No. Des. 947,135.

(57) **CLAIM**

The ornamental design for an LED proximity switch, as shown and described.

DESCRIPTION

FIG. 1 is front and right-side perspective view showing my new design;

FIG. 2 is a rear elevation thereof;

FIG. 3 is a front elevation thereof;

FIG. 4 is bottom plan view thereof;

FIG. 5 a top plan view thereof;

FIG. 6 is right side elevation thereof; and,

FIG. 7 a left side elevation thereof.

The broken lines represent portions of the LED proximity switch that form no part of the claimed design.

1 Claim, 3 Drawing Sheets
